ABSTRACT: The pulse motor drive system comprises a plurality of flip-flop circuits connected in an endless chain, each of the flip-flop circuits including a pair of input terminals and a pair of output terminals. At least one output terminal of each flip-flop circuit is connected to the input terminals of the flip-flop circuits on both sides thereof through gate circuits. The initial state of output signals for output terminals of all flip-flop circuits are determined by a reset signal and the state thus determined is shifted one by one by trigger pulses. Output conductors are connected between output terminals of every other flip-flop circuits and a conventional pulse motor to energize coils thereof in a predetermined order.

PULSE MOTOR DRIVE SYSTEMS

This invention relates to a novel pulse motor drive system for controlling the direction of rotation thereof by means of flip-flop circuits and gate circuits.

It is an object of this invention to provide a novel pulse motor drive system to control the direction of rotation thereof by alternately energizing m phase coil or coils and $(m+1)$ phase coils of the motor, where m represents a natural number selected such that $(2m+1)$ is equal to the number of phase coils of the pulse motor.

Another object of this invention is to provide a pulse motor drive system which readily enables to change the direction of rotation of the motor from forward to reverse or vice versa.

Still another object of this invention is to provide an improved pulse motor drive system which is reliable in operation and simple in construction.

To accomplish these and other objects in accordance with this invention, a plurality of identical flip-flop circuits are connected in an endless chain, each flip-flop circuit being provided with an input terminal, a complementary input terminal, an output terminal, and a complementary output terminal. The output terminal or both output terminals of each one of the flip-flop circuits are connected to both input terminals, i.e. input terminals and complementary input terminals of the flip-flop circuits situated on both sides thereof. Conductors of lead wires are connected to the output terminals of every other flip-flop circuits so as to energize selected coils of the pulse motor in a predetermined order. A reset signal operates to set a first half of flip-flop circuits and to reset a second half of the flip-flop circuits so that the former produces binary output signals "1" at respective output terminals and the latter produces binary output signals "0" at respective output terminals. Ever trigger pulse operates to reverse one flip-flop circuit in the first half and one flip-flop circuit in the second half in such a manner that successive halves of the flip-flop produce signals "1" at the output terminals while the other successive halves produce signals "0" at the output terminals.

In the accompanying drawings:

FIG. 1 is a block diagram of a first embodiment of a pulse motor drive system embodying this invention;

FIG. 2 is a chart showing output signals provided by respective flip-flop circuits in the pulse motor drive system when forward drive signals are applied thereto;

FIG. 3 is a chart showing output signals supplied to the pulse motor when forward drive signals are applied to the pulse motor drive system shown in FIG. 1;

FIG. 4 is a chart showing output signals provided by respective flip-flop circuits in the pulse motor drive system shown in FIG. 1 when reverse drive signals are applied thereto;

FIG. 5 is a similar chart showing output signals supplied to the pulse motor when reverse drive signals are applied to the pulse motor drive system shown in FIG. 1;

FIG. 6 shows a longitudinal section of a conventional pulse motor driven by the pulse motor drive system shown in FIG. 1;

FIG. 7 shows a block diagram of a second embodiment of the pulse motor drive system embodying this invention.

Generally, the present invention relates to a pulse motor drive system adapted to control a pulse motor provided with n stators and n rotor blocks which are individually magnetized by respective coils where n is a natural number equal to three or more.

Referring now to FIG. 1 of the accompanying drawings, there is shown a first embodiment of a pulse motor drive system of this invention adapted to control the direction of rotation of a conventional motor provided with five coils, five rotor blocks and five pairs of stators as shown in FIG. 6 wherein two coils and three coils are alternately energized to provide a half-pitch drive. Flip-flop circuits FF_1 through FF_{10} inclusive are provided with output terminals Q_1 through Q_{10} , complementary output terminals $\bar{Q}_1$ through $\bar{Q}_{10}$, input terminals J_1 through J_{10} , complementary input terminals K_1 through K_{10} , set terminals SD_1 through SD_{10} , reset terminals RD_1 through RD_{10} and trigger terminals T_1 through T_{10} , 75

respectively. Each of these flip-flop circuits has the same construction and operates identically. For the sake of brevity, hereinafter it is referred to as a "J-K flip-flop." The operation of the J-K flip-flop will be described with reference to the first J-K flip-flop FF_1 . This J-K flip-flop FF_1 generates output "1" and "0" at the respective output terminals Q_1 and $\bar{Q}_1$ when a trigger pulse is applied to trigger terminal T_1 where input signals "1" and "0" are being applied to input terminals J_1 and K_1 , respectively. The first J-K flip-flop FF_1 also generates outputs "0" and "1" at output terminals Q_1 and $\bar{Q}_1$, respectively, in response to the application of a trigger pulse to trigger terminal T_1 where input signals "0" and "1" are being applied to input terminals J_1 and K_1 , respectively. Furthermore, when input signals are not applied to both input terminals J_1 and K_1 , the first J-K flip-flop will not change the outputs from output terminals Q_1 and $\bar{Q}_1$ even if a trigger pulse is applied to trigger terminal T_1 . In this specification input and output signals, etc. are represented by a binary code system so that a higher or significant voltage and a lower or zero voltage are expressed by a binary "1" and a binary "0," respectively. A forward signal input conductor F for passing forward drive signals is connected to input terminals $1a, 3a, 5a, 7a, 9a, 11a, 13a, 15a, 17a$ and $19a$ of respective NAND circuits $12A, 14A, 16A, 18A, 20A, 22A, 24A, 26A, 28A$ and $30A$. Forward signal input conductor F is also connected to input terminals $1b, 3b, 5b, 7b, 9b, 11b, 13b, 15b, 17b$ and $19b$ of respective NAND circuits $12B, 14B, 16B, 18B, 20B, 22B, 24B, 26B, 28B$ and $30B$. Input terminals $1a, 3a, 5a, 7a, 9a, 11a, 13a, 15a, 17a$ and $19a$ and input terminals $b, 3b, 5b, 7b, 9b, 11b, 13b, 15b, 17b$ and $19b$ are referred to as odd input terminals. The NAND circuits $12A, 14A, 16A, 18A, 20A, 22A, 24A, 26A, 28A$ and $30A$ and NAND circuits $12B, 14B, 16B, 18B, 20B, 22B, 24B, 26B, 28B$ and $30B$ are herein referred to as AE-NAND circuits and BE-NAND circuits, respectively. The terms odd, "AE" and "BE" do not have any significant meanings but are used to distinguish them from each other. A reverse signal input conductor R for passing reverse drive signals is connected to input terminals $2a'4a'6a'8a'10a'12a'14a'16a'18a'$ and $20a'$ of NAND circuits $11A, 13A, 15A, 17A, 19A, 21A, 23A, 25A, 27A$ and $29A$, respectively. Input conductor R is further connected to input terminals $2b'4b'6b'8b'10b'12b'14b'16b'18b'$ and $20b'$ of respective NAND circuits $11B, 13B, 15B, 17B, 19B, 21B, 23B, 25B, 27B$ and $29B$. Input terminals $2a'4a'6a'8a'10a'12a'14a'16a'18a'$ and $20a'$; $2b'4b'6b'8b'10b'12b'14b'16b'18b'$ and $20b'$; NAND circuits $11A, 13A, 15A, 17A, 19A, 21A, 23A, 25A, 27A$, and $29A$; and NAND circuits $11B, 13B, 15B, 17B, 19B, 21B, 23B, 25B, 27B$ and $29B$ are herein referred to as "even input terminals," "AU-NAND circuits" and "BU-NAND circuits," respectively. Again the "even," "AU" and "BU" do not have any significant meanings but are used to distinguish them from each other. Each one of all AE, AU, BE and BU-NAND circuits having quite identical operation and construction produces signals "0" only at the time when signals "1" are applied simultaneously to their even and odd terminals whereas each produces signals "1" when a signal "1" is applied to their even or odd input terminals or when signals "1" are not applied to both of their input terminals.

Output terminals provided for the AE-NAND circuits are respectively connected to input terminals $A_1, A_2, A_3, A_4, A_5, A_6, A_7, A_8, A_9$ and A_{10} of AND circuits $1-A, 2A, 3A, 4A, 5A, 6A, 7A, 8A, 9A$ and $10A$ which are herein termed as A-AND circuits. Output terminals provided for AU-NAND circuits are also connected to input terminals $A_1'A_2'A_3'A_4'A_5'A_6'A_7'A_8'A_9'A_{10}'$ of the A-AND circuits, respectively. Output terminals provided for BE and BU-NAND circuits respectively connected to input terminals $B_1, B_2, B_3, B_4, B_5, B_6, B_7, B_8, B_9$, and B_{10} and to input terminals $B_1'B_2'B_3'B_4'B_5'B_6'B_7'B_8'B_9'$ and B_{10}' of AND circuits $1B, 2B, 3B, 4B, 5B, 6B, 7B, 8B, 9B$, and $10B$ which are termed as B-AND circuits hereinafter. Output terminals of A-AND circuits and B-AND circuits are respectively connected to input terminals $K_1, K_2, K_3, K_4, K_5, K_6, K_7, K_8, K_9$, and K_{10} and to the input terminals J_1, J_2, J_3 ,

$J_4, J_5, J_6, J_7, J_8, J_9$, and J_{10} of J-K flip-flops $FF_1, FF_2, FF_3, FF_4, FF_5, FF_6, FF_7, FF_8, FF_9$, and FF_{10} . All A and B-AND circuits have identical construction and produce output signals "1" only when signals "1" are applied simultaneously to both of their input terminals. Output terminals $-Q_1, Q_2, Q_3, Q_4, Q_5, Q_6, Q_7, Q_8$ and Q_{10} of J-K flip-flops are connected to the even input terminals $4a, 6a, 8a, 10a, 12a, 14a, 16a, 18a, 20a$ and $2a$ of AE-NAND circuits, respectively. These even input terminals are also connected to odd input terminals $19a', 1a', 3a', 5a', 7a', 9a', 11a', 13a', 15a'$ and $17a'$ of AU-NAND circuits, respectively. The output terminals or complementary output terminals $\bar{Q}_1, \bar{Q}_2, \bar{Q}_3, \bar{Q}_4, \bar{Q}_5, \bar{Q}_6, \bar{Q}_7, \bar{Q}_8, \bar{Q}_9$ and $\bar{Q}_{10}$ of J-K flip-flops are respectively connected to even input terminals $4b, 6b, 8b, 10b, 12b, 14b, 16b, 18b, 20b$ and $2b$ of the BE-circuits, these complementary outputs being also connected to odd input terminals $19b', 1b', 3b', 5b', 7b', 9b', 11b', 13b', 15b'$ and $17b'$ of the BU-NAND circuits, respectively.

A reset signal input conductor R_e for passing reset signals is connected to set terminals SD_1, SD_2, SD_3, SD_4 and SD_5 of J-K flip-flops FF_1, FF_2, FF_3, FF_4 and FF_5 , respectively and also to reset terminals RD_6, RD_7, RD_8, RD_9 and RD_{10} of the J-K flip-flops FF_6, FF_7, FF_8, FF_9 and FF_{10} .

A trigger pulse input conductor $\bar{T}$ for passing trigger signals or pulses is connected to trigger terminals $T_1, T_2, T_3, T_4, T_5, T_6, T_7, T_8, T_9$ and T_{10} of J-K flip-flops, respectively. Output terminals Q_1, Q_3, Q_5, Q_7 and Q_9 are further connected to a conventional pulse motor through output conductors I, II, III, IV and V. These conductors are connected to respective coils 101, 102, 103, 104, and 105 of the pulse motor through respective amplifiers 401, 102, 103, 404 and 405, as shown in FIG. 6. The illustrated pulse motor comprises a housing 501, five pairs of stators 201a and 201b 202a, and 202b, 203a and 203b, 204a and 204b, 205a and 205b which are secured to the housing, five cylindrical wound coils 101, 102, 103, 104, and 105 interposed between respective stator pairs and a rotor including five rotor blocks 301, 302, 303, 304 and 305 which are magnetically isolated from each other and are mounted on a shaft 502 rotatably journaled by housing 501.

Upon application of a reset pulse on reset conductor R_e , J-K flip-flops FF_1, FF_2, FF_3, FF_4 , and FF_5 are set and the other J-K flip-flops FF_6, FF_7, FF_8, FF_9 and FF_{10} are reset. In the set and reset conditions, output signals "1" are generated at output terminals $Q_1, Q_2, Q_3, Q_4, Q_5, \bar{Q}_6, \bar{Q}_7, \bar{Q}_8, Q_9$ and $\bar{Q}_{10}$ of J-K flip-flops FF_1 through FF_{10} inclusive and output signals "0" are generated at output terminals $\bar{Q}_1, \bar{Q}_2, \bar{Q}_3, \bar{Q}_4, \bar{Q}_5, Q_6, Q_7, Q_8, Q_9$ and Q_{10} of these flip-flops. Thus, output signals "1" at output terminals Q_1, Q_3 and Q_5 are applied to three coils 101, 102 and 103 respectively through output conductors I, II and III whereby these three coils are energized to magnetize three pairs of the stators 201a and 201b, 202a and 202b, 203a and 203b and three rotor blocks 301, 302 and 303 corresponding to said three pairs of the stators. Furthermore, output signals "1" appearing at output terminals $Q_1, Q_2, Q_3, Q_4, Q_5, \bar{Q}_6, \bar{Q}_7, \bar{Q}_8, \bar{Q}_9$ and $\bar{Q}_{10}$ are furnished to even input terminals $4a, 6a, 8a, 10a$ and $12a$ of the even AE-NAND circuits and to even input terminals $14b, 16b, 18b, 20b$ and $2b$ of the BE-NAND circuits and thence to odd input terminals $19a', 1a', 3a', 5a'$ and $7a'$ of the AU-NAND circuits and to the odd input terminals $9b', 11b', 13b', 15b'$ and $17b'$ of the BU-NAND circuits. However, in the set and reset conditions, the input terminals connected to output terminals $\bar{Q}_1, \bar{Q}_2, \bar{Q}_3, \bar{Q}_4, \bar{Q}_5, Q_6, Q_7, Q_8, Q_9$ and Q_{10} , i.e. even input terminals $4b, 6b, 8b, 10b$, and $12b$ of the BE-NAND circuits, the odd input terminals $19b', 1b', 3b', 5b'$ and $7b'$ of the BU-NAND circuits, even input terminals $14a, 16a, 18a, 20a$ and $2a$ of the AE-NAND circuits and odd input terminals $9a', 11a', 13a', 15a'$ and $17a'$ of the AU-NAND circuits, are not supplied with any significant electric voltage so that output signals "0" or no significant voltage are generated thereat. Thus, A-AND circuits 1A, 2A, 3A, 4A, 5A, 6A, 7A, 8A, 9A and 10A generate output signals "1" which are applied to input terminals $K_1, K_2, K_3, K_4, K_5, K_6, K_7, K_8, K_9$ and K_{10} of the J-K flip-flops since both of all AU-NAND circuits

and all AE-NAND circuits generate output signals "1" since they are not simultaneously supplied with signals "1" at their even and odd input terminals.

B-AND circuits 1B, 2B, 3B, 4B, 5B, 6B, 7B, 8B, 9B and 10B also generate signals "1" which are supplied to input terminals J_1 through J_{10} inclusive of J-K flip-flops since both of all BU-NAND circuits and BE-NAND circuits generate output signals "1" since they are not simultaneously supplied with signals "1" at their even and odd input terminals.

10 When an input signal "1" and an input signal "0" are applied to forward signal input conductor F and to reverse signal input conductor R , respectively, the input signal "1" is furnished to the odd input terminals of AE-NAND circuits

12A, 14A, 16A, 18A, 20A, 22A, 24A, 26A, 28A, and 30A and of BE-NAND circuits 12B, 14B, 16B, 18B, 20B, 22B, 24B, 26B, 28B and 30B through forward signal input conductor F , and input signal "0" is furnished to the even input terminals of AU-NAND circuits 11A, 13A, 15A, 17A, 19A, 21A, 23A, 25A, 27A and 29A and of BU-NAND circuits 11B, 13B, 15B, 17B, 19B, 21B, 23B, 25B, 27B and 29B through reverse signal input conductor R . Accordingly, AE-NAND circuits

14A, 16A, 18A, 20A and 22A and BE-NAND circuits 24B, 26B, 28B, 30B and 12B generate signals "0" since these NAND circuits are simultaneously supplied with signals "1" to their even and odd input terminals. Remaining NAND circuits, i.e. all AU-NAND circuits and BU-NAND circuits, AE-NAND circuits 24A, 26A, 28A, 30A and 12A and BE-NAND circuits 14B, 16B, 18B, 20B, 22B of the BE-NAND circuits,

30 generate output signals "1" since they are not simultaneously supplied with signals "1" at both of their input terminals. Therefore A-AND circuits 2A, 3A, 4A, 5A and 6A and B-AND circuits 7B, 8B, 9B, 10B and 1B generate signal "0" and A-AND circuits 7A, 8A, 9A, 10A and 1A and B-AND circuits 35 2B, 3B, 4B, 5B, and 6B generate signals "1" to apply the signals "1" to the input terminals $K_1, J_2, J_3, J_4, J_5, J_6, K_7, K_8, K_9$ and K_{10} of respective flip-flops $FF_1, FF_2, FF_3, FF_4, FF_5, FF_6, FF_7, FF_8, FF_9$ and FF_{10} and to apply signals "0" to input terminals $J_1, K_2, K_3, K_4, K_5, K_6, J_7, J_8, J_9$ and J_{10} thereof.

40 40 When a forward trigger pulse No. 1 (the term "forward trigger pulse" means a trigger pulse applied to trigger input conductor $\bar{T}$ when a forward signal is applied to forward signal input conductor F) is applied to trigger input terminals T_1 through T_{10} inclusive J-K flip-flops FF_1 and FF_6 are switched or reversed thus generating output signals "1" at output terminals $\bar{Q}_1$ and Q_6 instead of output terminals Q_1 and $\bar{Q}_6$. But the other J-K flip-flops $FF_2, FF_3, FF_4, FF_5, FF_7, FF_8, FF_9$ and FF_{10} are maintained in their previous state i.e. J-K flip-flops FF_2, FF_3, FF_4 and FF_5 are supplied with input signals "1" at their input terminals J_2, J_3, J_4 and J_5 to produce output signals "1" at their output terminals Q_2, Q_3, Q_4 and Q_5 and J-K flip-flops FF_7, FF_8, FF_9 and FF_{10} are supplied with input signals "1" at their input terminals K_7, K_8, K_9 and K_{10} to produce output signals "1" at their output terminals $\bar{Q}_7, \bar{Q}_8, \bar{Q}_9$ and $\bar{Q}_{10}$.

45 55 Thus, output signals "1" to be supplied to the electric pulse motor are obtained at conductors II and III connected to output terminals Q_3 and Q_5 thus energizing coils 102 and 103. As the result, the signal "0" from output terminals Q_1 is supplied to odd input terminal $19a'$ of AU-NAND circuit 29A and to even input terminal $4a$ of AE-NAND circuit 14A. As a result, NAND circuit 14A changed its output signal from "0" to "1" since only a single signal "1" is supplied to the odd input terminal $3a$ from forward input conductor F . Thus, A-AND circuit 2A supplies a signal "1" to input terminal K_2 , since AU-NAND circuit 13A continues to supply a signal "1" to A-AND circuit 2A. On the other hand, a signal "1" from output terminal $\bar{Q}_1$ is supplied to even input terminal $19b'$ of BU-NAND circuit 29B and to even input terminal $4b$ of BE-NAND circuit

60 65 70 14B whereby NAND circuit 14B changes its output signal from "1" to "0" since a signal "1" is supplied to odd input terminal $3b$ from the forward signal input conductor F . Thus B-AND circuit 2B supplies a signal "0" to input terminal J_2 since NAND circuit 13B continues to produce a signal "1." Similarly, as a result of the reversal of J-K flip-flop FF_6 a signal

"1" from output terminal $\bar{Q}_8$ is supplied to odd input terminal $9a'$ of AU-NAND circuit 19A and to even input terminal $14a$ of AE-NAND circuit 24A causing this AE-NAND circuit 24A to change its output signal from "1" to "0" since the odd input terminal $13a$ of AE-NAND circuit 24A (after "0") is supplied with a signal "1" from forward input conductor F. Thus A-AND circuit 7A supplied a signal "0" to input terminal K_7 since the output of AU-NAND circuit 23A is still "0." On the other hand, the signal "0" from output terminal $\bar{Q}_8$ is supplied to odd input terminal $9b'$ of BU-NAND circuit 19B and to even input terminal $14b$ of BE-NAND circuit 24B thus causing BE-NAND circuit 24B to change its output signal from "0" to "1". Thus, B-AND circuit 7B supplies a signal "1" to input terminal J_7 since odd input terminal $13b$ is supplied with a signal "1" from forward input conductor F and the output signal of BU-NAND circuit 23B is still "1." In brief, forward trigger pulse No. 1 switches or reverses flip-flops FF₁ and FF₆ and as a result of the reversal of J-K flip-flop FF₁, the output signal from A-AND circuit 2A is changed from "0" to "1" whereas the output signal from B-AND circuit 2B is changed from "1" to "0" whereby input terminal K_2 receives a significant voltage, i.e. signal "1" instead of input terminal J_2 . In the same manner, input terminal J_7 of J-K flip-flop FF₇ receives a signal "1" instead of its input terminal K_7 .

When the operation caused by the forward trigger pulse No. 1 has been completed a forward trigger pulse No. 2 is applied to the pulse motor drive system embodying this invention. Upon application of the forward trigger pulse No. 2 to trigger terminals T_1 through T_{10} inclusive through input trigger conductor $\bar{T}$, J-K flip-flops FF₂ and FF₇ will be reversed so as to generate output signals "1" at their output terminals $\bar{Q}_2$ and Q_7 respectively. However, the other flip-flops FF₁, FF₃, FF₄, FF₅, FF₆, FF₈, FF₉ and FF₁₀ are maintained in their previous state i.e. J-K flip-flops FF₃, FF₄, FF₅ and FF₆ are furnished with input signals "1" at their input terminals J_3 , J_4 , J_5 and J_6 to produce output signals "1" at their respective output terminals Q_3 , Q_4 , Q_5 and Q_6 and J-K flip-flops FF₈, FF₉, FF₁₀, and FF₁ are supplied with input signals "1" at their input terminals K_8 , K_9 , K_{10} and K_1 to produce output signals "1" at their output terminals $\bar{Q}_8$, $\bar{Q}_9$, $\bar{Q}_{10}$ and $\bar{Q}_1$, respectively. Thus, output signals "1" are supplied to the elective pulse motor from output conductors II, III and IV connected to output terminals Q_3 , Q_5 and Q_7 , thus energizing coils 102, 103 and 104. As a result of the reversal of the J-K flip-flop FF₂, the signal supplied from A-AND circuit 3A to input terminal K_3 of J-K flip-flop FF₃ is changed from "0" to "1" since the output signal of AU-NAND circuit 15A is still "1" and the output signal of AE-NAND circuit 16A is changed from "0" to "1" by the change of output signal "0" from the output terminal Q_2 to the even input terminal $6a$. On the other hand, the signal supplied to input terminal J_3 of J-K flip-flop FF₃ from B-AND circuit 3B is changed from "1" to "0" since the output signal of BU-NAND circuit 15B is still "1" and the output signal of BE-NAND circuit 16B has been changed from "1" to "0" due to the change in the output signal "1" from the output terminal Q_2 to even input terminal $6b$ of BE-NAND circuit 16B.

Similarly, as a result of the reversal of J-K flip-flop FF₇, the signal supplied from A-AND circuit 8A to input terminal K_8 of J-K flip-flop FF₇ is changed from "1" to "0" since the output signal of AU-NAND circuit 25A is still "1" whereas the output of AE-NAND circuit 26A has been changed from "1" to "0" since both even and odd input terminals $15a$ and $16a$ of NAND circuit 26A are supplied with signals "1" from output terminal Q_7 and forward input conductor F, respectively. On the other hand the output signal of B-AND circuit 8B supplied to input terminal J_8 of J-K flip-flop FF₈ is changed from "0" to "1" since the output terminal of BU-NAND circuit 25B is still "1" and the output signal of BE-NAND circuit 26B has been changed from "0" to "1" because odd input terminal $15b$ is supplied with a signal "1" from forward input conductor F while input terminal $16b$ with a signal "0" from output terminal $\bar{Q}_7$. Accordingly, when J-K flip-flops FF₂ and FF₇ are reversed by the action of a forward trigger pulse No. 2, their

input terminals which are applied with signals "1" will be changed from J_3 to K_3 and from K_8 to J_8 , respectively.

Upon completion of the operation caused by the trigger pulse No. 2 a forward trigger pulse No. 3 is supplied to the pulse motor drive system of this invention. When a trigger pulse No. 3 is applied to trigger input terminals T_1 through T_{10} inclusive, J-K flip-flops FF₃ and FF₈ are reversed in the same manner as has been described in connection with forward trigger pulse No. 1 and No. 2 whereby the output terminals for producing signals "1" are switched from Q_3 to $\bar{Q}_3$ and from $\bar{Q}_8$ to Q_8 , respectively. Therefore, output signals "1" supplied to the pulse motor are obtained on output conductors III and IV to energize coils 103 and 104 and the input terminals of J-K flip-flops FF₄ and FF₉ which are supplied with the signal "1" are changed from J_4 to K_4 and from K_9 to J_9 to prepare J-K flip-flops FF₄ and FF₉ for the reversal caused by a forward trigger pulse No. 4.

In this manner, two J-K flip-flops are reversed by a forward trigger pulse so that each of two other J-K flip-flops immediately to the right of said first-mentioned two flip-flops are switched to other state to receive signals "1" to prepare for a next forward trigger pulse. Therefore, while a signal "1" is being applied through forward signal input conductor F, when forward trigger pulses No. 1 through No. 10 inclusive are successively applied to trigger input terminals T_1 through T_{10} inclusive of the J-K flip-flops, the output signals from output terminals Q_1 through Q_{10} inclusive will change according to the first chart shown in FIG. 2. As will be noted from the first chart output signals from respective output terminals caused by a forward trigger pulse No. 10 are the same as in the initial condition, that is the reset condition. Therefore, when the next trigger pulse or a forward trigger pulse No. 11 is applied to respective trigger input terminals subsequent to forward trigger pulse No. 10, then output signals from output terminals Q_1 through Q_{10} inclusive will be changed to the same conditions as when trigger pulse No. 1 was applied.

As long as forward trigger pulses are supplied, output signals shown in the first chart are repeated every 10 forward trigger pulses so that the signals supplied to the pulse motor from output terminals Q_1 , Q_3 , Q_5 , Q_7 and Q_9 through output conductors I, II, III, IV and V will change according to a second chart shown in FIG. 3. The second chart shows that two signals "1" and three signals "1" are obtained alternately to energize two coils and three coils according to the same sequence.

Suppose now that a signal "1" is supplied to reverse signal input conductor F subsequent to forward trigger pulse No. 3 for the purpose of rotating the pulse motor in the reverse direction. Input terminals connected to reverse signal input conductor R, i.e. even input terminals $2a'$, $4a'$, $6a'$, $8a'$, $10a'$, $12a'$, $14a'$, $16a'$, $18a'$ and $20a'$ of AU-NAND circuits and even input terminals $a2b'$, $4b'$, $6b'$, $8b'$, $10b'$, $12b'$, $14b'$, $16b'$, $18b'$ and $20b'$ of BU-NAND circuits are supplied with signals "1". It is to be remembered that application of trigger pulse No. 3 results in the generation of output signals "1" at output terminals $\bar{Q}_1$, $\bar{Q}_2$, $\bar{Q}_3$, Q_4 , Q_5 , Q_6 , Q_7 , Q_8 , $\bar{Q}_9$ and $\bar{Q}_{10}$ and output signals "0" at the output terminals Q_1 , Q_2 , Q_3 , $\bar{Q}_4$, $\bar{Q}_5$, $\bar{Q}_6$, $\bar{Q}_7$, $\bar{Q}_8$, Q_9 and Q_{10} . Odd input terminals $5a'$, $7a'$, $9a'$, $11a'$ and $13a'$ of AU-NAND circuits and odd input terminals $1b'$, $3b'$, $15b'$, $17b'$ and $19b'$ of BU-NAND circuits which are associated with output terminals Q_4 , Q_5 , Q_6 , Q_7 , Q_8 , $\bar{Q}_2$, $\bar{Q}_3$, $\bar{Q}_8$, $\bar{Q}_{10}$ and $\bar{Q}_1$, respectively, are supplied with signals "1." The other odd input terminals $1a'$, $3a'$, $15a'$, $17a'$ and $19a'$ of AU-NAND circuits and the other odd input terminals $5b'$, $7b'$, $9b'$ and $13b'$ which are associated with output terminals Q_2 , Q_3 , Q_9 , Q_{10} , Q , $\bar{Q}_4$, $\bar{Q}_5$, $\bar{Q}_6$, $\bar{Q}_7$ and $\bar{Q}_8$, respectively, are supplied with signals "0." Accordingly, AU-NAND circuits 11A, 13A, 25A, 27A and 29A and BU-NAND circuits 15B, 17B, 19B, 21B and 23B generate signals "1" since they are not simultaneously supplied with signals "1" at their even and odd input terminals. On the other hand, AU-NAND circuits 15A, 17A, 19A, 21A and 23A and BU-NAND circuits 11B, 13B, 25B, 27B and 29B produce no significant voltage or signal "0"

because they are supplied with signals "1" at their even and odd input terminals simultaneously. Furthermore, all AE-NAND circuits 12A, 14A, 16A, 18A, 20A, 22A, 24A, 26A, 28A and 30A and all BE-NAND circuits 12B, 14B, 16B, 18B, 20B, 22B, 24B, 26B, 28B and 30B produce signals "1" since odd input terminals 1a, 3a, 5a, 7a, 9a, 11a, 13a, 15a, 17a and 19a of AE-NAND circuits and odd input terminals 1b, 3b, 5b, 7b, 9b, 11b, 13b, 15b, 17b and 19b of BE-NAND circuits are connected to forward signal input conductor F which is not supplied with a signal "1" at this time. Accordingly, A-AND circuits 1A, 2A, 8A, 9A and 10A and B-AND circuits 3B, 4B, 5B, 6B and 7B generate signals "1" respectively by the simultaneous application of signals "1" at both of their input terminals, thus applying signals "1" to associated input terminals K₁, K₂, K₈, K₉, K₁₀, J₃, J₄, J₅, J₆ and J₇. The other A-AND circuits 3A, 4A, 5A, 6A and 7A and the other B-AND circuits 1B, 2B, 8B, 9B and 10B generate signals "0" whereby input terminals K₃, K₄, K₅, K₆, K₇, J₁, J₂, J₈ and J₁₀ associated therewith are supplied with signals "0." Summarizing the above, when a signal "1" is applied to reverse signal input conductor R instead of forward signal input conductor F subsequent to the trigger pulse No. 3, input terminals which have received signals "1" are changed from K₃, K₄, J₈ and J₉ to J₃, J₄, K₈ and K₉. When a reverse trigger pulse No. 1 (by the term "reverse trigger pulse" is meant a trigger pulse which is applied to trigger input conductor $\bar{T}$ while a reverse signal "1" is being applied to reverse signal input conductor R) is applied to trigger input terminals T₁ through T₁₀ inclusive of the J-K flip-flops, J-K flip-flops FF₃ and FF₈ are switched to produce signals "1" from their output terminals Q₃ and $\bar{Q}_8$, respectively, due to the application of the signals "1" to input terminals J₃ and K₈. However, the other J-K flip-flops FF₁, FF₂, FF₄, FF₅, FF₆, FF₇, FF₉, and FF₁₀ will not be reversed since they are supplied with signals which correspond to output terminals producing signals "1" At this time, the output signals "1" which are applied to the pulse motor are obtained from output conductors II, III and IV connected to output terminals Q₃, Q₅ and Q₇ thus energizing coils 102, 103 and 104 of the motor. Therefore, output signals from output terminals of all J-K flip-flops are identical to those generated when a forward trigger No. 2 is applied to forward signal input conductor F. As a result of the application of a reverse trigger pulse No. 1, input terminals of two J-K flip-flops FF₂ and FF₇ to be supplied with signals "1" are changed from K₂ to J₂ and from J₇ to K₇ to prepare for a reverse trigger pulse No. 2. Upon application of the reverse trigger pulse No. 2 to trigger pulse input conductor $\bar{T}$, J-K flip-flops FF₂ and FF₇ are switched whereby output signals from output terminals of all J-K flip-flops become identical to those generated when the forward trigger pulse No. 1 was applied to trigger input terminal $\bar{T}$ and when input terminals J₁ and K₆ were supplied with signals "1" instead of input terminals K₁ and J₆. In this manner, to rotate the pulse motor in the reverse direction the output signals from J-K flip-flops are instantly switched back by the reverse trigger pulses without any troubles even if the forward trigger pulse was changed to the reverse trigger pulse in a very short time. FIG. 4 is a third chart showing states of the output signals from output terminals Q₁ through Q₁₀ inclusive when reverse trigger pulses from No. 1 to No. 10 are successively applied. These states of output signals are obtained repeatedly every 10 reverse trigger pulses. FIG. 5, is a fourth chart showing the states of output signals appearing at output conductors I, II, III, IV and V connected to output terminals, that is the sequence of energization of the coils provided for the pulse motor shown in FIG. 6. As can be noted from the fourth chart, two coils and three coils are energized alternately and the sequence of the energization is just opposite to that of the second chart shown in FIG. 3.

Referring now to FIG. 7, there is shown a modified pulse motor drive system of this invention for controlling an electric pulse motor provided with three coils by alternately energizing one and two thereof. In this embodiment, flip-flops FF₅₁, FF₅₂, FF₅₃, FF₅₄, FF₅₅ and FF₅₆ have the same construction and

operate in the same manner as flip-flop FF₁ used in the first embodiment and these flip-flops are provided with output terminals Q₅₁, Q₅₂, Q₅₃, Q₅₄, Q₅₅ and Q₅₆, output terminals or complementary output terminals $\bar{Q}_{51}$, $\bar{Q}_{52}$, $\bar{Q}_{53}$, $\bar{Q}_{54}$, $\bar{Q}_{55}$ and $\bar{Q}_{56}$, input terminals J₅₁, J₅₂, J₅₃, J₅₄, J₅₅ and J₅₆, input terminals or complementary input terminals K₅₁, K₅₂, K₅₃, K₅₄, K₅₅ and K₅₆, set terminals SD₅₁, SD₅₂, SD₅₃, SD₅₄, SD₅₅ and SD₅₆, reset terminals RD₅₁, RD₅₂, RD₅₃, RD₅₄, RD₅₅ and RD₅₆ and trigger input terminals T₅₁, T₅₂, T₅₃, T₅₄, T₅₅ and T₅₆, respectively. A forward signal input conductor F_a is connected to odd input terminals 111a, 113a, 115a, 117a, 119a and 121a of respective AE-NAND gate circuits 112A, 114A, 116A, 118A, 120A and 122A. A reverse signal input conductor R_a is connected to even input terminals 112a', 114a', 116a', 118a', 120a' and 122a' of respective AU-NAND circuits 111A, 113A, 115A, 117A, 119A and 121A. Output terminals of all AE-NAND circuits are connected to AND circuits 101A, 102A, 103A, 104A, 105A and 106A, respectively. Output terminals AU-NAND circuits 111A, 113A, 115A, 117A, 119A and 121A are also connected to AND circuits 101A, 102A, 103A, 104A, 105A and 106A, respectively. Furthermore, these AND circuits are respectively connected to input terminals, J₅₁ and K₅₁, J₅₂ and K₅₂, J₅₃ and K₅₃, J₅₄ and K₅₄, J₅₅ and K₅₅, and J₅₆ and K₅₆ to apply output signals thereto. NOT circuits 51C, 52C, 53C, 54C, 55C and 56C are interposed between AND circuit 101A and input terminal J₅₁, AND circuit 102A and input terminal J₅₂, AND circuit 103A and input terminal J₅₃, AND circuit 104A and input terminal J₅₄, AND circuit 105A and input terminal J₅₅ and between AND circuit 106A and input terminal J₅₆, respectively. Each one of the NOT circuits has the same construction and operation and functions to invert the signal applied by the NAND circuit, that is, it produces an output signal "1" when a signal "1" is not applied thereto whereas it produces an output signal "0" when a signal "1" is applied thereto. A trigger input conductor $\bar{T}_a$ for passing trigger pulses is connected to trigger input terminals T₅₁, T₅₂, T₅₃, T₅₄, T₅₅ and T₅₆ of the J-K flip-flops. An input conductor Res for set and reset signals is connected to set terminals SD₅₁, SD₅₂ and SD₅₃ of respective flip-flops and to rest terminals RD₅₄, RD₅₅ and RD₅₆ of respective flip-flops. Output terminals Q₅₁, Q₅₂, Q₅₃, Q₅₄, Q₅₅ and Q₅₆ are respectively connected to even input terminals 114a, 116a, 118a, 120a, 122a and 112a of respective AE-NAND circuits 114A, 116A, 118A, 120A, 122A and 112A and thence to odd input terminals 121a', 111a', 115a', 117a' and 119a' of respective AU-NAND circuits 121A, 113A, 115A, 117A, and 119A. Output terminals Q₅₁, Q₅₃ and Q₅₅ are further connected to an electric pulse motor of the conventional type, not shown, through output conductors I', II' and III'. The pulse motor is provided with three stationary coils and a rotor which is driven by alternately energizing one coil and two coils. The operation of this modified pulse motor drive system is as follows: Application of a reset pulse signal to reset conductor Res causes J-K flip-flops FF₅₁, FF₅₂ and FF₅₃ to set and the other J-K flip-flops FF₅₄, FF₅₅ and FF₅₆ to reset. In the set and reset conditions, output signals "1" are generated at output terminals Q₅₁, Q₅₂, Q₅₃, Q₅₄, Q₅₅ and Q₅₆ of J-K flip-flops whereas output signals "0" are generated at output terminals Q₅₁, Q₅₂, Q₅₃, Q₅₄, Q₅₅ and Q₅₆ thereof. Accordingly, the output signals "1" appearing at output terminals Q₅₁ and Q₅₃ are applied to the pulse motor to energize its two coils through output conductors I' and II'. Furthermore, the output signals "1" appearing at output terminals Q₅₁, Q₅₂ and Q₅₃ are applied to even input terminals 114a, 116a and 118a of respective AE-NAND circuits 114A, 116A and 118A, and thence to odd input terminals 121a', 111a' and 113a' of AU-NAND circuits 121A, 111A and 113A, respectively. While these NAND circuits are in their set and reset conditions, when input signals "1" and "0" are applied to forward signal input conductor F_a and reverse signal input conductor R_a, respectively, the input signals "1" are supplied to odd input terminals 111a, 113a, 115a, 117a, 119a and 121a of AE-NAND circuits, respectively. Accordingly, AE-NAND circuits 114A, 116A, and 118A

generate signals "0" since these NAND circuits will simultaneously be supplied with signals "1" to their even and odd input terminals. The other AE-NAND circuits 112A, 120A and 122A generate signals "1" since these NAND circuits will not simultaneously be applied with signals "1" at both of their input terminals. On the other hand, all AU-NAND circuits 111A, 113A, 115A, 117A, 119A and 121A generate output signals "1" since their even input terminals 112a', 114a', 116a', 118a', 120a' and 122a' are connected to reverse signal input conductor Ra which is not applied with any significant voltage during the operation of the forward rotation. AND circuits 101A, 105A and 106A which are simultaneously supplied with signals "1" from associated NAND circuits generate signals "1" which are applied to input terminals K₅₁, K₅₃ and K₅₄. The other AND circuits 102A, 103A and 104A which are supplied with signals "1" alone from associated AU-NAND circuits 113A, 115A and 117A generate signals "0" whereby NOT circuits 52C, 53C and 54C generate signals "1" which are applied to input terminals J₅₂, J₅₃ and J₅₄, respectively.

Thereafter, when a forward trigger pulse No. 1 (as above described, the term "forward trigger pulse" means a trigger pulse applied to trigger input conductor $\bar{T}_a$ when a forward signal is being applied to forward signal input conductor Fa) is applied to trigger input terminals T₅₁, T₅₃, T₅₅, T₅₄, T₅₅ and T₅₆, output terminals of J-K flip-flops FF₅₁ and FF₅₄ will be switched to generate signals "1" from output terminals Q₅₁ to $\bar{Q}_{51}$ and output terminals Q₅₄ to Q₅₄, respectively, since J-K flip-flops FF₅₁ and FF₅₄ are supplied with signals "1" at their input terminals K₅₁ and J₅₄, respectively. However, the other J-K flip-flops FF₅₂, FF₅₃, FF₅₅ and FF₅₆ are maintained in their previous conditions since they are supplied with signals "1" to their input terminals J₅₂, J₅₃, K₅₅ and K₅₆ to produce output signals "1" at their output terminals Q₅₂, Q₅₃, $\bar{Q}_{55}$ and $\bar{Q}_{56}$, respectively. Therefore, an output signal "1" which is applied to the pulse motor having three coils is obtained from output terminal Q₅₃ via output conductor II'. As a result of switching or reversal of flip-flop FF₁, the output signal of AND-circuit 102A is changed from "0" to "1" since the output signal from output terminal Q₅₁ is changed from "1" to 1 with a result that NAND circuit 114A generates an output signal "1" which is supplied to AND circuit 102A. Similarly, as a result of the reversal of J-K flip-flop FF₅₄, the output signal of AND circuit 105A is caused to change from "1" to "0" whereby NOT circuit 55C supplies signal "1" to the input terminal J₅₅ since the output signal from the output terminal Q₅₄ is changed from "0" to "1" with a result that NAND circuit 120 changes its output signal from "1" to "0." Upon application of a forward trigger pulse No. 2 upon trigger input terminals T₅₁, T₅₂, T₅₃, T₅₄, T₅₅ and T₅₆ through trigger input conductor $\bar{T}_a$ subsequent to the application of a forward trigger pulse No. 1 J-K flip-flops FF₅₂ and FF₅₅ are caused to reverse at this time so as to generate output signals "1" at their output terminals $\bar{Q}_{52}$ and Q₅₅, respectively whereas the other flip-flops FF₅₁, FF₅₃, FF₅₄ and FF₅₆ are maintained in the previous states. At this time, the output signals "1" are produced from output terminals Q₅₃ and Q₅₅ and are applied to the pulse motor through output conductors II' and III'. Input terminals for receiving signals "1" are changed from input terminals J₅₃ and to input terminals K₅₅ and J₅₆, respectively. In this manner, when a forward trigger pulse is supplied to trigger input conductor $\bar{T}_a$, two of J-K flip-flops FF₅₁, FF₅₂, FF₅₃, FF₅₄, FF₅₅ and FF₅₆ are reversed and the input terminals of the J-K flip-flops to the right of the reversed J-K flip-flops are switched to receive signals "1" to prepare for the reversal caused by a next succeeding forward trigger pulse. Combinations of a single output signal "1" and two output signals "0" and of a single output signal "0" and two output signals "1" are obtained alternately

from output conductors I', II' and III' to drive the pulse motor having three coils. Upon application of a reverse trigger pulse upon trigger input conductor $\bar{T}_a$, two of J-K flip-flops FF₅₁, FF₅₂, FF₅₃, FF₅₄, FF₅₅ and FF₅₆ are reversed and the input terminals of J-K flip-flops to the left of the reversed flip-flops are switched to receive signals "1" to prepare for the reversal caused by a next succeeding reverse trigger pulse. In this manner, output signals are regularly produced by the reverse trigger pulses from output conductors I', II' and III' to drive the pulse motor in the reverse direction.

While the invention has been shown and described in terms of preferred embodiments thereof, it should be understood that the invention is by no means limited thereto and that many changes and modifications will be obvious to one skilled in the art without departing from the spirit and scope of the invention.

What is claimed is:

1. A pulse motor drive system for controlling the direction of rotation of a pulse motor having a plurality of driving coils comprising a plurality of flip-flops capable of changing output signals thereof in accordance with input signals supplied to said flip-flops, each one of said flip-flops being provided with a pair of input terminals and at least one output terminal, the number of said flip-flops being twice the number of said driving coils; a plurality of gate circuits interconnecting said flip-flops in ring formation and being responsive to output signals from the output terminals of each flip-flop to supply input signals to the input terminals of the next successive flip-flop in accordance with said output signals from the next preceding flip-flop; conductors connected to said output terminal of alternate ones of said flip-flops to supply output signals from said last-mentioned output terminals to said driving coils of said pulse motor;
2. A pulse motor drive system according to claim 1, wherein a reset conductor connected to each of said flip-flops for setting a first half of said flip-flops and for resetting a second half of said flip-flops upon the occurrence of a reset signal;
3. A trigger input conductor connected to supply trigger pulses to each of said flip-flops to switch output signals of a flip-flop in said first half and a flip-flop in said second half;
4. A forward signal input conductor connected to said gate circuits to supply a signal for commanding forward rotation of said pulse motor; and
5. A reverse signal input conductor connected to said gate circuits to supply a signal for commanding reverse rotation of said pulse motor.
6. A pulse motor drive system according to claim 1, wherein each one of said gate circuits comprises a first gate circuit and a second gate circuit,
7. Said first gate circuit including a first NAND circuit, a second NAND circuit and an AND circuit,
8. Said AND circuit being responsive to output signals from said first and second NAND circuits and capable of supplying signals to the input terminal of one of said flip-flops, said first NAND circuit being connected to said forward input conductor and to the output terminal of the next preceding flip-flop, said second NAND circuit being connected to said reverse signal input conductor and to the output terminal of the next succeeding flip-flop, said second gate circuit being provided between said one of said flip-flops and an adjacent flip-flop.
9. The pulse motor drive system according to claim 2, wherein said second gate circuit is similar to said first gate circuit.
10. The pulse motor drive system according to claim 2, wherein said second gate circuit is connected as a NOT circuit between said one of said flip-flops and said AND circuit for inverting output signals from said AND circuit.

UNITED STATES PATENT OFFICE
CERTIFICATE OF CORRECTIONPatent No. 3,614,580 : Dated October 19, 1971Inventor(s) Kunihiko Eto

It is certified that error appears in the above-identified patent and that said Letters Patent are hereby corrected as shown below:

2a', 4a', 6a',...and 20a'--
line 42, for "terminals 2b'4b'6b'...and 20b'" read
--terminals 2b', 4b', 6b',...and 20b'--;
line 44, for "terminals 2a'4a'6a'8a'10a'" read --terminals
2a', 4a', 6a', 8a', 10a'--
line 45, for "12a' 14a' 16a' 18a" read --12a', 14a',
16a', 18a'--
line 45, for "6b'8b'10b'12B'14b'16b'" read --6b', 8b',
10b', 12b', 14b', 16b'--
line 63, for "circuits 1-A," read --circuits 1A,--

UNITED STATES PATENT OFFICE
CERTIFICATE OF CORRECTION

Patent No. 3,614,580 : Dated October 19, 1971

Inventor(s) Kunihiko Eto

It is certified that error appears in the above-identified patent and that said Letters Patent are hereby corrected as shown below:

Page 2

Column 2 - continued

line 66, for "A₁'A₂'A₃'A₄'" read --A₁', A₂', A₃', A₄'--

line 66, for "A₇" read --A₇--;

line 68, for "circuits respective-" read --circuits are
respective- --;

line 69, for "B₈" read --B₈--;

line 70, omit the comma "," in the first instance;

line 70, for "B₁'B₂'...B₈" read --B₁', B₂', ... B₈'--;

line 71 for "B₉" read --B₉--;

Column 3 line 1, for "J₄," read --J₄--;

line 5, for "-Q₁," read --Q₁--;

Column 4 line 46, "Q₆" in the first instance should read --Q₆--;

line 58, for "terminals" read --terminal--;

Column 5 line 1, for "Q₆" read --Q₆--;

line 5, for "24A (after '0') is supplied" read --24A is
supplied--;

line 43, for "Q₃." read --Q₃--;

line 44, omit the comma "," in the first instance;

UNITED STATES PATENT OFFICE
CERTIFICATE OF CORRECTIONPatent No. 3,614,580 : Dated October 19, 1971Inventor(s) Kunihiko Eto

It is certified that error appears in the above-identified patent and that said Letters Patent are hereby corrected as shown below:

Page 3

Column 6 line 63, for "Q₈" in the second instance, read --Q₉--;
line 66, for "7b', 9b'" read --7b', 9b', 11b'--;
Column 7 line 18, for "k₇," read --K₇--;
line 34, for "signals which" read --signals "1" at their
input terminals K1, K2, J4, J5, J6, J7, K9 and
K10--;
line 62, for "10" read --ten--;
Column 8 line 45, for "111a', 115a'" read --111a', 113a', 115a'--;
line 46, for "121A, 113A" read --121A, 111A, 113A--;
line 48, for "though" read --through--;
Column 9 line 24, for "conductor Fa" " read --conductor Fa)--;

Signed and sealed this 18th day of July 1972.
